UNITED STATES PATENT OFFICE

WELL PACKER

Otis T. Broyles, Houston, Tex.

Application August 16, 1948, Serial No. 44,441

8 Claims. (Cl. 166—12)

This invention relates to a well anchor.

An object of the invention is to provide a well anchor of the character described which is of such construction that it may be run into the well in disengaged position and the anchor then expanded at the selected point to provide a support for any desired purpose, e. g., against which a packer may be expanded to form a seal between an outer casing and an inner string of pipe, and which may be released when it is desired to remove the anchor from the well.

It is a further object of the invention to provide equipment of the character described whereby the anchor, when located at the desired point in the well may be set or expanded to provide a support by a motion in one direction of the means on which it is run into the well and which, when desired, may be manipulated by a motion of the running means in the opposite direction at least a certain distance but less than a greater predetermined distance to release the anchor and to maintain the same in released position so that the anchor may be moved again with the running means moving in said one direction without setting the anchor in the well and which may thereafter be manipulated by motion of the running means in said opposite direction beyond said predetermined distance to return the anchor to its original condition wherein it will be set by a motion of the running means in said one direction.

It is still another object of the invention to provide a well anchor which may be lowered into the well with either end uppermost, and set, released and withdrawn with either an operating string of pipe or a wire line.

Another object of the invention is to provide a well packer incorporating a well anchor of the foregoing type.

Other objects and advantages will be apparent from the following specifications which are illustrated by the accompanying drawings, wherein—

Figure 1 is a side elevation, partly in section, of one form of the invention in which the anchor is incorporated in a well packer and showing the packer and the anchor included therein in collapsed position while being run into the well.

Figure 2 is a side elevation, partly in section, of the packer and its anchor as expanded, or set, in the well to form a seal between the outer casing and inner pipe.

Figure 3 is a side elevation, partly in section, illustrating the packer and its anchor after the

release and contraction thereof to be removed from the well.

Figure 4 is a cross-sectional view taken on the line 4—4 of Figure 3.

5 Figure 5 is a cross-sectional view taken on the line 5-5 of Figure 3.

Figure 6 is a side view, partly in section, of another embodiment of the invention as being run into the well.

10 Figure 7 is a side elevation, partly in section, of said embodiment upon release of the packer and its anchor to permit its withdrawal from the well, and

Figure 8 is a fragmentary, vertical, sectional view illustrating another means of lowering and withdrawing the packer and its anchor.

Referring now more particularly to Figures 1 to 5 of the drawings wherein like numerals of reference designate the same parts in each of the figures, the numeral 1 designates the inner string of pipe, whose lower end forms the packer mandrel 1-a.

On the lower end of the mandrel there is a relatively thick collar 2 and above this collar and surrounding said mandrel there is an expansible packer sleeve 3 formed of rubber or similar expansible material.

Around the mandrel and abutting the upper end of the sleeve 3 there is a slip expander 4 whose lower end rests on the upper end of the packer sleeve and which tapers upwardly externally.

Spaced above the expander 4 the mandrel has an external coupling 5 and spaced above the coupling 5, the required distance, there is an annular external stop 6 secured on the mandrel.

Slidable on, but in tight frictional engagement with, the mandrel there is a tubular cage sup-

port 7 which is provided with the upper and lower external stops 8 and 9 at its upper and lower ends respectively. This cage support 7 is limited in its downward movement by the stop 6 and in its upward movement by the external coupling 10 on the string 11.

45 On the support 7 there is a cylindrical cage 11 having the upper and lower internal annular flanges 12 and 13 which fit closely over the support 7 and space the cage from said support.

50 Beneath said cage and support there are the
casing engaging slips 14 whose inner sides are
tapered downwardly and outwardly in such
manner as to conform to the taper of the ex-
pander 4 and whose outer sides are provided
55 with upwardly pitched teeth. These slips are

suspended from the cage by means of flexible arms 15.

The cage is provided with the external outwardly bowed friction members commonly known as wiper springs 16. The lower ends of these wiper springs are secured to the cage and their upper ends are free and work in external vertical grooves, as 17, in said cage. They frictionally engage the inside of the well casing to hold the cage at any selected point in the casing.

Immediately above the stop 9 the support 7 is provided with a vertical slot 18 therethrough and there is a flexible latch 19 whose lower end is secured to the stop 9 and whose upper end 15 is free but of substantial arcuate formation.

The mandrel has an external arcuate notch 20 in which the upper arcuate end of the latch 19 engages when the equipment is in inactive position for being lowered into the well.

In operation the equipment is assembled as shown in Figure 1 with the cage and cage support in their upper position and with the flexible latch 19 engaged in the notch 20.

In this position the equipment may be lowered into the well bore with the wiper springs 16 in contact with the well casing thus holding the slips 14 in their upper position out of contact with the expander 4. When a point has been reached where it is desired to set the packer an upward pull may be taken on the string 1. The wiper springs 16 will hold the cage 11 stationary and the expander 4 will enter and expand, the slips 14 into engagement with the well casing, as shown in Figure 2, and the stop 9 will engage the lower end of the cage so as to stop the upward movement of the cage support and upon further upward movement of the string 1 the collar 2 engaging the lower end of the packer sleeve 3 will expand said packer into close contact with the surrounding well casing and at the same time will move the notch 20 above the inwardly curved end of the latch 19 so as to unseat said latch from said notch. The support or sleeve 7 fits string 1 tight enough to prevent the sleeve from moving down under its own weight and unseating the latch before the cage 11 has passed over it.

The packer sleeve will thus form a fluid tight seal between the outer well casing and inner tubing.

When it is desired to release the packer and withdraw it from the well the operating string 1 may be lowered and since the support 7 is fitted closely about the string the said support will move downwardly with the string while the cage 11 remains stationary. The outwardly turned upper end of the latch 19 will pass beneath the lower end of said cage and then upon upward movement of the string 1 said latch will engage underneath the flange 13, as shown in Figure 3. The support or sleeve 7 fits string 1 tight enough so that the force required to overcome the frictional engagement therebetween and cause the sleeve to slide is greater than the force needed to cause latch 19 to pass beneath the lower end of the cage on downward movement of the string. This downward movement of the string 1 will carry the expander 4 beneath the slips 14, as shown in Figure 3, permitting the 70 packer 3 to collapse or contract and upon subsequent upward movement of the string 1 the latch 19 will hold the cage and slips in elevated position relative to the expander and upon engagement of the stop 6 with the lower end of

the support 7 the equipment may be withdrawn from the well with the slips securely locked or retained in their position above the expander 4 so that there will be no liability of the slips coming into contact with the well casing.

As illustrated there is shown only one notch 20 and a corresponding flexible latch 19 but in practical use a plurality of latches and notches may be provided.

In the embodiment illustrated in Figures 6 and 7 there is a relatively thick collar 2a screwed onto the lower end of the string of pipe and above this collar and surrounding said mandrel there is an expandable sleeve 3a formed of rubber or similar expandable material.

Around the inner pipe and abutting the upper end of the sleeve 3a there is an expander 4a which tapers upwardly externally and whose lower end abuts the packer sleeve 3a.

In this form of the invention the lower end of the mandrel 1b which forms the lower part of the inner string abuts the upper end of said expander 4a, as shown in Figure 6.

The mandrel 1b is outwardly thickened near its lower end thus forming an upwardly facing, outwardly flared, external annular shoulder 21.

There is a sleeve-like cage support 22 slidably mounted on the mandrel above said shoulder 21. Its lower end is tapered downwardly and inwardly and its upper end is outwardly thickened forming an external downwardly facing shoulder 23 and above said shoulder is provided with an external annular groove 24.

On the support 22 there is a sleeve-like cage 25 and depending from this cage there are the casing engaging slips 26 whose inner surfaces are downwardly flared to conform in shape to the external shape of the expander 4a and whose outer surfaces are toothed. These slips are maintained in place by the flexible arms 26a whose lower ends are attached to the slips.

These arms are also attached to the lower end of the cage and are outwardly bowed forming wiper springs 27, above said point of attachment, and their upper ends are of arcuate formation forming latches which latch into the grooves 24, as illustrated in Figure 6. These wiper springs frictionally engage the well casing while the equipment is being lowered or withdrawn from the well.

The lower end of the cage is also provided with notches, as 28, and secured, at their upper ends, to the cage are the flexible spring dogs 29 whose lower ends extend through said notches and are free.

In going into the well the embodiment illustrated in Figures 6 and 7 may be assembled, as shown in Figure 6, and lowered into the well with the upper ends of the wiper springs 27 seated in the groove 24 thus latching the cage 25 and the slips 26 in their upper position above the expander 4a and with the lower ends of the dogs 29 resting against the outer surface of the support 22.

When the equipment has been lowered to a point where it is desired to expand the packer the operating string 1 may be pulled upwardly but the support 22, the cage 25 and the slips 26 will be held stationary until the expander 4a engages the inner tapering surfaces of the said slips. In the meantime the shoulder 21 will have engaged the lower end of the support 22 and said support will have been elevated to unlatch the upper ends of the wiper springs 27 from the groove 24 and upon further upward movement the slips

4a will be expanded and the outwardly curved upper ends of the wiper springs **27** will have engaged underneath the shoulder **23**. Also the lower or free ends of the dogs **29** will have passed beneath the lower end of the support **22**. A further upward pull on the operating string **1** will, in an obvious manner, cause an expansion of the sleeve **3a** to form a seal with the well casing. Should it now be desired to release the packer the operating string may be moved downwardly thus relieving the endwise compressive force on the packer sleeve **3a** and allowing it to collapse and also carrying the shoulder **21** beneath the lower ends of the dogs **29** and thereafter an upward pull on the string **1** will cause the shoulder **21** to engage the lower ends of the dogs **29** thus holding the cage **25** and the slips **26** elevated with respect to the expander **4a** so that the equipment may be withdrawn from the well and the engaging slips **27** will be maintained in their retracted position above and out of contact with the expander **4a** so that said slips will not be liable to engage the well casing and the equipment may then be readily withdrawn from the well.

Instead of running the apparatus into the well on a string of tubing as shown in Figures 1-3, the apparatus may be run on a wire line as shown in Figure 8 where the numeral **41** designates a section of pipe or tubing whose lower end is screwed into the upper end of the coupling **10** and whose upper end is provided with a socket **42** secured thereto by a pin **43**. A wire line or cable **44** has its lower end secured in the socket **42**. As in conventional wire line operations, jars will be used in the wire line so that the apparatus can be positively driven down into the well when its weight alone is insufficient to move it down and so that the apparatus can be drawn upward with greater force than the static pull of the draw works at times when the static pull alone is insufficient. At other times the apparatus will be operated simply by raising or lowering it. The reciprocations of the apparatus to actuate it with a wire line, whether by weight and simple pull alone or by jarring, are the same as when the apparatus is run on a string of tubing.

Since in wire line operations the cable is removed from the well rather than left in the well as is the tubing when the apparatus is run on tubing, provision is made for disconnecting the cable from the apparatus while the apparatus is still in the well. This is accomplished by breaking shear pin **43** after the apparatus has been set. Later, if it is desired to remove the apparatus, a conventional grappling tool is lowered into the well and engaged with section **41**, and the apparatus may then be operated in the manner previously described to remove it from the well.

It is to be further noted that the assembly of either the form shown in Figure 1 or the form shown in Figure 6 may be reversed and be lowered and set in the well and withdrawn.

With the form shown in Figures 1 to 5, inclusive, if it be desired to reverse the equipment it may be adjusted into the position shown in Figure 3, prior to lowering into the well and then lowered with the cage **11** at the lower end and the packer sleeve **3** at the upper end. When the point where the packer is to be set has been reached the tool is then elevated and the parts will assume the relative positions shown in Figure 1 and then lowered to the set position shown in Figure 2.

If the form shown in Figures 6 and 7 are 75

lowered in reverse position the parts should be adjusted to the position shown in Figure 7 and then lowered to the desired location and then elevated until the parts assume the position shown in Figure 6. The setting string or setting equipment may then be lowered and the expander **4a** will come into contact with and expand the slips **26** into engagement with the well casing and upon further lowering of the operating string the packer sleeve **3a** will be expanded and form a seal with the surrounding casing.

The drawings and description are illustrative of what are now considered to be preferred forms of the invention by way of illustration only and not by way of limitation while the broad principle of the invention will be defined by the appended claims. In this connection it will be noted that both illustrated embodiments of the invention include a support in the form of the lower end of the inner pipe string including the mandrel, and that the slip expander is carried on this support, being held against radial movement by its encirclement of the support and against axial movement by the packer, although since the packer is made of rubber, which has a low modulus of elasticity compared to steel, it can be relatively easily deformed which allows limited axial movement of the slip expander. This combination of support and slip expander may for convenience be called a body assembly.

To the body assembly there is connected in both embodiments a slip assembly including the cage, the friction members or wiper springs, the slips, and the flexible connecting arms which limit or substantially prevent axial movement of the slips relative to the cage while allowing radial movement by flexing of the arms.

The connection between the assemblies includes interengaging parts to limit relative radial movement of the assemblies. In both embodiments these parts include the cage surrounding the inner string.

The connection between the assemblies also includes an outer stop in the form of the coupling **10** on the body assembly of each embodiment which limits movement of the slip assembly relative to the body assembly in the retracting direction, i. e., the direction separating the slips and expander, and an inner stop in the form of the stop **6** in the first embodiment and the enlarged lower end of section **1b** in the second embodiment which limits movement of the slip assembly in the opposite or setting direction. The inner stop in each embodiment prevents the slips and expander from being engaged so far as to burst the pipe. The outer stop in each case enables the slip assembly to be moved in the well along with the body assembly when the latter is moved in the retracting direction. In order that the slip assembly may be moved in the well along with the body assembly when the latter is moved in the setting direction without setting the slips, the connection also includes a middle stop in the form of latch elements on the slip assembly and pipe assembly which when moved into engageable position limit the relative motion of the assemblies in the setting direction more than does the inner stop. In the first embodiment these latch elements include the latch **19** and flange **13**. In the second embodiment they include the dogs **29** and shoulder **21**.

In both embodiments the latch elements are moved into engageable position by relative motion of the assemblies of at least a certain dis-

tance in the retracting direction from the slip set position, and in both assemblies further motion in the same direction beyond a predetermined distance moves the latch elements into nonengageable position. In both of the particular embodiments shown this is accomplished by means of a sleeve member reciprocably connected to the assemblies, namely, the tubular cage support 7 in the first embodiment and the sleeve-like cage support 22 in the second embodiment. In both embodiments the sleeve is semi-locked to one of the assemblies to prevent relative reciprocation thereof except upon exertion of a force greater than a predetermined amount but less than that needed to slide the wiper springs in the well. In the first embodiment the sleeve is frictionally semi-locked to the inner string by the inner portion of the sleeve which tightly engages the inner string. In the second embodiment the sleeve is semi-locked to the cage by the latches formed on the opposite ends of the wiper springs, the latches engaging the outer portion of the sleeve. These latches when engaged with groove 24 prevent any relative axial motion of the cage and sleeve and when next to the enlarged end of the sleeve prevent relative axial motion of the cage and sleeve in the direction tending to re-engage the latches in the groove.

In both embodiments the range of relative axial movement between the sleeve and the assembly to which it is not semi-locked is less than the full range of relative axial movement of the two assemblies as limited by the inner and outer stops, and less than that needed to set the slips and in order to achieve the full range of movement required to set the slips it is necessary to exert enough force to cause axial movement between the sleeve and the assembly to which it is semi-locked. In the first embodiment it is engagement of the stops 8 and 9 with flanges 12 and 13 which restrict relative axial motion of the cage relative to the sleeve. In the second embodiment it is engagement of the sleeve ends with coupling 10 and shoulder 21 which restrict relative axial motion of the sleeve relative to the mandrel.

In both embodiments the latch elements of the middle stop are actuated by relative motion of the sleeve and the assembly to which it is semi-locked and it is the relative position corresponding to maximum motion in the retracting direction that corresponds to the non-engageable position of the latch elements. In the first embodiment the latch 19 is controlled by sleeve 7. When the sleeve is in its outermost position on the string, i. e., most removed from the slip expander, the latch 19 is in notch 20 where the latch is non-engageable by flange 13. In the second embodiment the dogs 29 are controlled by sleeve 22. When the sleeve is in its innermost position relative to the cage, i. e., when it is nearest the slips, the dogs 29 are riding on the sleeve where they are non-engageable by shoulder 21.

In both embodiments the middle stop constituted by the latch elements is a one-way stop in that it prevents relative motion of the two assemblies only in the setting direction and if the assemblies have already been moved in the setting direction beyond the limit set by the middle stop, they can be moved in the opposite or retracting direction without interference by the middle stop. In the first embodiment, when the flange 13 is below the latch 19, as shown in Figure 2, the flange can be moved upwardly past the latch

even though it is not lying in the notch 20. In the second embodiment when the dogs 29 are below shoulder 21 riding on part 1-b of the string, they can be moved upwardly past the shoulder even though the sleeve is not in position to keep the dogs radially spaced from the string a distance as great as the diameter of part 1-b.

In both embodiments, the actuation of the latch elements of the middle stop between the non-engageable and engageable positions is accomplished independent of gravity, the sleeve controlling the latch elements being moved positively by operator applied forces, namely, forces applied by the operator to the string. This is important in order that the anchors be operable with either the slips or the expander uppermost. It is especially important that the motion from non-engageable to engageable position be positive when the anchor is positioned with its slips above the expander for in this case upward motion of the string corresponds to relative motion of the assemblies in the setting direction and if the middle stop is not placed in engageable position it will be impossible to get the equipment out of the well.

In the first embodiment the stops 8 and 9 on the sleeve 7 are positively engaged by the flanges 12 and 13 on the cage so that the sleeve is positively moved, and the semi-locking of the sleeve to the string of the body assembly insures that the motion occurs only when the slip assembly, i. e. the cage portion thereof, is in the proper position. The latch 19 can not be moved out of the notch 20 until the flange 13 has passed beyond the latch in the setting direction. The latch 19 cannot be moved back into the notch 20 until the flange 13 has passed beyond the latch in the retracting direction so that if motion of the string is stopped before the latch is moved back into the notch, motion of the string can be reversed without setting the slip.

In the second embodiment the ends of the sleeve 22 are positively engaged by the coupling 10 and shoulder 21 so that the sleeve is positively moved, and the semi-locking of the sleeve to the cage of the slip assembly insures that the motion occurs only when the body assembly, i. e. the string portion thereof is in proper position. The dogs 29 cannot be moved off the sleeve 22 until the shoulder 21 on the string is adjacent the sleeve causing the dogs to pass over to part 16 beyond the shoulder 21 in the setting direction. The dogs 29 cannot be moved back onto sleeve 22 until the dogs 29 have passed beyond shoulder 21 in the retracting direction, for the latch ends of the wiper springs abut against the underside of the enlarged upper end of the sleeve containing the depression or groove 24, this disposal of parts constituting part of the semi-locking of the sleeve to the slip assembly as before set forth. It is only when the upper end of the sleeve contacts the coupling 10 that the dogs can once again be moved onto the sleeve, but this is long after the dogs have passed beyond shoulder 21 so that if desired the motion of the string can be reversed after the dogs have passed the shoulder and before they have moved onto the sleeve again, and the string can then be moved in the well in the slip setting direction without setting the slips.

What I claim is:

1. A well anchor comprising a body assembly including a support adapted to be connected to means for running the anchor into the well, and a slip expander carried by the support; a slip assembly including a slip adapted to engage a well

pipe when moved thereagainst by said expander, a friction element to engage the pipe, and a connection between said element and said slip restricting relative movement therebetween in a direction parallel to the pipe axis while permitting radial motion of the slip relative to the pipe axis; and a connection between said slip assembly and said body assembly including means limiting relative radial movement of said assemblies, stop means limiting relative axial movement of said assemblies to a certain range near one extreme of which said slip is wholly disengaged from said expander and near the other extreme of which said slip is engaged by said expander sufficiently to cause the slip to move radially outwardly to set by engagement with the pipe, latch means in engageable position restricting said range to prevent motion toward said other extreme far enough to allow said slip to set and in non-engageable position permitting motion over the full extent of said range, and control means positively actuatable solely by reciprocation of said means for running the anchor into the well and independent of gravity to control the position of said latch means.

2. A well anchor comprising a body assembly including a support adapted to be connected to means for running the anchor into the well, and a slip expander carried by the support; a slip assembly including a slip adapted to engage a well pipe when moved thereagainst by said expander, a friction element to engage the pipe, and a connection between said element and said slip restricting relative movement therebetween in a direction parallel to the pipe axis while permitting radial motion of the slip relative to the pipe axis; and a connection between said slip assembly and said body assembly including means limiting relative radial movement of said assemblies, stop means limiting relative axial movement of said assemblies to a certain range near one extreme of which said slip is wholly disengaged from said expander and near the other extreme of which said slip is engaged by said expander sufficiently to cause the slip to move radially outwardly to set by engagement with the pipe, latch means in engageable position restricting said range to prevent motion toward said other extreme far enough to allow said slip to set and in non-engageable position permitting motion over the full extent of said range, and control means to move said latch means to the engageable position positively actuated independent of gravity solely by axial translation of said body assembly relative to said slip assembly from the position in which the slip is set at least a certain distance in the direction causing separation of the slip and expander sufficient to unset the slip and to move said latch means to the non-engageable position positively actuated independent of gravity solely by further axial translation of said body assembly relative to said slip assembly to at least a predetermined greater distance from the slip set position toward the slip disengaged position.

3. A well anchor comprising a body assembly including a support adapted to be connected to means for running the anchor into the well, and a slip expander carried by the support; a slip assembly including a slip adapted to engage a well pipe when moved thereagainst by said expander, a friction element to engage the pipe, and a connection between said element and said slip restricting relative movement therebetween in a direction parallel to the pipe axis while permitting radial motion of the slip relative to the pipe axis; and a connection between said slip assembly and

said body assembly including means limiting relative radial movement of said assemblies, stop means limiting relative axial movement of said assemblies to a certain range near one extreme of which said slip is wholly disengaged from said expander and near the other extreme of which said slip is engaged by said expander sufficient to cause the slip to move radially outwardly to set by engagement with the pipe, latch means in engageable position restricting said range to prevent motion toward said other extreme far enough to allow said slip to set and in non-engageable position permitting motion over the full extent of said range, and control means positively actuatable solely by reciprocation of said means for running the anchor into the well and independent of gravity to control the position of said latch means, said control means including a member axially reciprocably connected to said assemblies adapted in one axial position to hold said latch elements so that they cannot engage and in another axial position to move said latch elements into engageable position, semilocking means other than said latch elements to hold said member to one of said assemblies to prevent relative reciprocation thereof except upon exertion of a certain force thereon greater than a predetermined force but less than that required to slide said friction element in the pipe, and inter-engaging stops on said member and the other of said assemblies to limit relative axial reciprocation thereof in order that said certain force may be exerted on said member by translation of said other assembly, said semilocking means being effective in at least two different relative positions of said member and said one assembly corresponding to engageable position of said latch elements and non-engageable position of said latch elements.

4. A well anchor comprising a body assembly including a support adapted to be connected to means for running the anchor into the well, and a slip expander carried by the support; a slip assembly including a slip adapted to engage a well pipe when moved thereagainst by said expander, a friction element to engage the pipe, and a connection between said element and said slip restricting relative movement therebetween in a direction parallel to the pipe axis while permitting radial motion of the slip relative to the pipe axis; and a connection between said slip assembly and said body assembly including means limiting relative radial movement of said assemblies, stop means limiting relative axial movement of said assemblies to a certain range near one extreme of which said slip is wholly disengaged from said expander and near the other extreme of which said slip is engaged by said expander sufficiently to cause the slip to move radially outwardly to set by engagement with the pipe, latch means in engageable position restricting said range to prevent motion toward said other extreme far enough to allow said slip to set and in non-engageable position permitting motion over the full extent of said range, and control means positively actuatable solely by reciprocation of said means for running the anchor into the well and independent of gravity to control the position of said latch means, said control means including a member axially reciprocably connected to said body assembly, the last said connection making a tight frictioned engagement between said member and said body assembly preventing even relative axial translation thereof except upon exertion of at least a certain force, said

force being less the force required to overcome the resistance of said friction element to move the slip assembly axially in the well; said slip assembly being axially reciprocably connected to said member, stops on said member limiting relative axial reciprocation of said member and slip assembly to a range which is less than said full range of relative motion between said assemblies, an aperture in said body assembly beneath said member, an aperture in said member which in one position of said member relative to said body assembly coincides with the aperture in said body assembly, said latch means including a spring latch mounted on said member in said aperture therein and urged by the spring thereof against said body assembly, said latch extending into the path of axial reciprocation of said slip assembly relative to said member at a point between said stops and preventing relative motion past said latch in the slip setting direction except when said member is in position such that its aperture coincides with that of said body assembly in which position said latch moves into said aperture in said body assembly and out of said path of axial reciprocation of said slip assembly relative to said member.

5. A well anchor comprising a body assembly including a support adapted to be connected to means for running the anchor into the well, and a slip expander carried by the support; a slip assembly including a slip adapted to engage a well pipe when moved thereagainst by said expander, a friction element to engage the pipe, and a connection between said element and said slip restricting relative movement therebetween in a direction parallel to the pipe axis while permitting radial motion of the slip relative to the pipe axis; and a connection between said slip assembly and said body assembly including means limiting relative radial movement of said assemblies, stop means limiting relative axial movement of said assemblies to a certain range near one extreme of which said slip is wholly disengaged from said expander and near the other extreme of which said slip is engaged by said expander sufficiently to cause the slip to move radially outwardly to set by engagement with the pipe, latch means in engageable position restricting said range to prevent motion toward said other extreme far enough to allow said slip to set and in non-engageable position permitting motion over the full extent of said range, and control means positively actuatable solely by reciprocation of said means for running the anchor into the well and independent of gravity to control the position of said latch means, said control means including a member axially reciprocably connected to said slip assembly, the last said connection including a spring latch carried by said slip assembly and an enlarged portion on said member having a depression therein adapted to receive said latch, the last said connection preventing any relative axial translation of said member and slip assembly when said spring latch is in said depression except upon exertion of at least a certain force and when said spring latch is not in said depression but is adjacent said enlarged portion preventing relative axial translation thereof in the direction tending to move said spring latch into said depression except upon exertion of at least a certain force, said certain forces being less than the force required to overcome the resistance of said friction element to move the slip assembly axially in the well, said

member being axially reciprocably connected to said body assembly, stops on said body assembly limiting relative axial reciprocation of said member and said body assembly to a range which is less than said full range of relative motion between said assemblies, said latch means including a spring dog carried by said slip assembly and which when said member is in a position relative to said slip assembly other than that in which said spring latch is in said depression is engageably by the one of the last said stops that limits motion of the sleeve and the slip assembly to which it is semi-locked relative to said body assembly in the slip setting direction, said member when in a position relative to said slip assembly in which said spring latch is in said depression extending beneath said dog and holding it from engagement by the last said stop.

6. A well anchor comprising a cylindrical body carrying a conical slip expander, a sleeve around said body in tight frictional engagement therewith but axially reciprocable thereon upon exertion of a force large enough to overcome the friction, a cage around said sleeve reciprocable axially thereon, slips carried by said cage adapted to engage said expander, stops on said body limiting reciprocation of said sleeve on said body, stops on said sleeve limiting reciprocation of said cage on said sleeve, a notch in said body, an aperture in said sleeve, a spring latch on said sleeve urged by its spring into said notch when said aperture overlies said notch but otherwise projecting into the path of travel of said cage on said sleeve to further restrict the range of reciprocation of said cage on said sleeve, and friction means carried by said cage to engage a well wall.

7. A well anchor comprising a cylindrical body carrying a conical slip expander, a sleeve around said body axially reciprocable thereon, a cage around said sleeve axially reciprocable thereon, slips carried by said cage adapted to engage said expander, said sleeve having an enlarged end with an annular groove therein, said cage carrying a spring latch, the spring of said latch urging it radially inward, said spring latch being adapted when disposed in said groove to hold said cage against axial movement relative to said sleeve except upon exertion of a force large enough to overcome the spring of said latch and said spring latch being adapted when disposed on said sleeve adjacent said enlarged end to prevent relative axial movement of said sleeve and cage in the direction tending to move said latch into said groove except upon exertion of a force large enough to overcome the spring of the latch, said cage carrying a spring dog that rests on said sleeve when said latch is in said groove but which otherwise extends beyond the sleeve and rests on said body, said body having an enlarged portion near the expander beyond which said sleeve cannot move but of no larger outer diameter than said sleeve and forming a shoulder engageable by said dog when on the smaller portion of the body, a stop on the smaller portion of said body limiting travel of the sleeve in the direction away from the large portion of the body, a stop on the larger portion of the body limiting motion of the cage relative thereto, and a stop on the sleeve preventing motion of the cage thereon in the direction toward the enlarged end of the sleeve beyond engagement of said latch in said groove, and friction means carried by said cage to engage a well wall.

8. A well anchor comprising a body assembly

13

including a support, means at the upper end of the support for connecting the support to means for running the anchor into the well, and a slip expander carried by the support having a slip engaging surface flaring downwardly toward the lower end of the support; a slip assembly including a slip adapted to engage a well pipe when moved thereagainst by said expander and having an expander engaging surface flaring in the same direction as the slip engaging surface of the expander, a friction element to engage the pipe and a connection between said element and said slip restricting relative movement therebetween in a direction parallel to the pipe axis while permitting radial motion of the slip relative to the pipe axis; and a connection between said slip assembly and said body assembly including means limiting relative radial movement of said assemblies, stop means limiting relative axial movement of said assemblies to a certain range near one extreme of which said slip is wholly disengaged from said expander and near the other

14

5 extreme end of which said slip is engaged by said expander sufficiently to cause the slip to move radially outwardly to set by engagement with the pipe, latch means in engageable position restricting said range to prevent motion toward said other extreme far enough to allow said slip to set and in non-engageable position permitting motion over the full extent of said range, and control means actuatable solely by reciprocation of 10 said means for running the anchor into the well to control the position of said latch means.

OTIS T. BROYLES.
